PISTON PACKING-RING.

1,181,774.

Specification of Letters Patent.

Patented May 2, 1916.

Application filed September 19, 1914. Serial No. 862,520.

To all whom it may concern:

Be it known that I, JAMES S. LAVELL, a citizen of the United States, residing at Schenectady, county of Schenectady, and 5 State of New York, have invented certain new and useful Improvements in Piston Packing-Rings, of which the following is a specification.

The invention relates to such improvements and consists of the novel construction and combination of parts hereinafter described and subsequently claimed.

Reference may be had to the accompanying drawings, and the reference characters 15 marked thereon, which form a part of this specification. Similar characters refer to similar parts in the several figures therein.

Figure 1 of the drawings is a plan view of 20 a piston-packing-ring made in accordance with my invention. Fig. 2 is a view in side elevation of the same. Fig. 3 is a view in side elevation, partly in section, of the cut resilient inner ring.

The principal object of the invention is to 25 provide for a close contact between the piston-ring and the cylinder, throughout the peripheral extent of the ring.

In carrying out my invention I employ a 30 cut resilient inner ring, 1, adapted to be confined under compression within an outer ring formed of three equal segments, 2, rabbed at their ends, 6, to make lapping engagement with each other and form substantially tight joints when the ring is confined 35 within the cylinder. The ends of the cut inner ring, 1, preferably form a lapping joint, as by cutting through the ring diagonally, as shown at 3 in Fig. 3.

The three segments, 2, of the outer ring 40 have their outer surfaces turned or dressed to form together a true cylindrical surface adapted to closely fit the interior of the cylinder for which the ring is intended, and each of the segments, 2, is made thicker at 45 about its middle than at its ends, thus providing at its middle a point, or comparatively small area, of contact with the outer surface of the cut inner ring, 1. The ends of the respective segments, 2, are thus 50 slightly spaced away at 5 from the inner ring, 1, thus providing for a slight rocking movement of the separate segments, 2, about their respective points of contact, 4, with the inner ring, permitting each segment to ad-

just itself to the inner wall of the cylinder 55 independently of the other segments. As the interior of the cylinder becomes worn, this capability for independent self-adjustment of the segments, 2, enables the ring to make very close contact with the inner surface of the cylinder.

By employing three segments in the outer ring and having the inner resilient ring bear upon the respective segments only at their middle points, the resilient force of the inner 65 ring is always effectively and equally distributed among the segments of the outer ring; and the rocking movement, whereby each segment of the outer ring is free to adjust itself, causes the outward pressure of 70 the inner ring to be quite uniformly distributed to all parts of the outer ring.

As a preferred form for the segments, 2, I have shown the inner surface of each segment formed as an arc eccentric to the outer 75 surface, so that each segment is meniscoidal in form and gradually tapers from its thicker middle portion to its respective ends.

What I claim as new and desire to secure by Letters Patent is—

1. A piston-packing-ring comprising an outer segmental ring divided into three equal segments, the outer surfaces of which form a cylindrical surface corresponding in diameter with the interior of the cylinder for 85 which the ring is adapted, and a cut resilient inner ring adapted to be confined under compression within said segmental ring, the several segments being thicker at the middle than at the ends, whereby they make contact 90 only at their middle with said inner ring.

2. A piston-packing-ring comprising an outer segmental ring having three equal meniscoidal segments, each having an outer surface forming an arc of the same radius as 95 the interior of the cylinder for which the ring is adapted, and an inner surface forming an arc eccentric to said outer surface, and a cut resilient inner ring adapted to be confined under compression within said segmental outer ring, in simple contact with the middle points of the respective segments.

In testimony whereof, I have hereunto set my hand this 14th day of September, 1914.

JAMES S. LAVELL.
